CLAIM

The ornamental design for a coat stand, as shown and described.

DESCRIPTION

FIG. 1 is a perspective view of a coat stand, showing my new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is a perspective view showing my new design connected to a support unit;

FIG. 9 is a perspective view showing my new design connected to another support unit; and,

FIG. 10 is a perspective view showing my new design arranged with a wall support unit.

The broken lines depict environment that forms no part of the claimed design.

1 Claim, 10 Drawing Sheets
